UNITED STATES PATENT OFFICE

119,535

DESIGN FOR A WEDDING DRESS ENSEMBLE

Jane Rosener, New York, N. Y.

Application January 2, 1940, Serial No. 89,252

Term of patent 3½ years

To all whom it may concern:

Be it known that I, Jane Rosener, a citizen of the United States, residing in New York city, in the county of New York and State of New York, have invented a new, original, and ornamental Design for a Wedding Dress Ensemble, of which the following is a specification, reference being had to the accompanying drawings, forming part thereof.

Fig. 1 is the front view of a wedding dress ensemble showing my design;

Fig. 2 is the rear view of the wedding dress ensemble on a reduced scale;

Fig. 3 is a front view of the coat portion of the ensemble shown in Fig. 1 with the detachable, trail over-skirt portion removed.

Fig. 4 is the front view of the dress portion of the ensemble, and

Fig. 5 is the rear view thereof, on a reduced scale.

I claim:

The ornamental design for a wedding dress ensemble, substantially as shown.

JANE ROSENER.
